SCRAPER

John H. McKean and Everett K. McKean, Alvin,
Tex., assignors to Stanolind Oil and Gas Com-
pany, Tulsa, Okla., a corporation of Delaware

Application April 17, 1940, Serial No. 330,057

4 Claims. (Cl. 166—18)

This invention relates to scrapers designed to remove deposits from the interiors of tubes, pipes and the like. More particularly it relates to scrapers for the removal of deposits from wells and still more particularly to scrapers for the removal of paraffin and similar deposits from the tubings of oil wells.

In many different connections deposits are built up on the interiors of tubings and similar conduits and it is often desired to remove these deposits. One particularly serious problem of this type exists in oil wells producing certain types of fluids notably crude oil containing large amounts of wax. As such fluids progress up the tubing of a well the pressure drops with the result that some of the lighter hydrocarbons are vaporized. At the same time the temperature is lowered with the result that waxy materials, commonly known as paraffin, and sometimes other materials of an asphaltic or resinous nature are thrown out and deposited on the walls of the tubing, particularly in the upper sections thereof. These deposits frequently reach such proportions that the capacity of the well is seriously reduced and in fact the well may completely plug. It has therefore long been the custom in connection with wells of this sort to remove these deposits by various means including the use of solvents and the running of scrapers. In general the use of solvents for the removal of these deposits has not been found very satisfactory and, on the other hand, the use of scrapers has been found time-consuming and expensive due to the unsatisfactory devices heretofore used. In general the prior art scrapers have not been successful in completely and expeditiously removing difficult deposits in a single run. This is due in large measure to the fact that these devices have served only to cut grooves or swaths through the paraffin without completely removing it and much difficulty has been encountered due to the balling up of the paraffin above the cutting knives or similar elements used in the prior art scrapers.

It is an object of our invention to provide new and improved scrapers for removing deposits from tubes and the like. More particularly it is an object of our invention to provide a superior scraper for removing deposits from wells and particularly for removing deposits such as paraffin from the tubing of oil wells.

A more particular object of our invention is to provide a scraper of the type mentioned which will completely remove the deposits. Another particular object of our invention is to provide a scraper which will not cause balling up of the

deposit ahead of the cutting elements and which will, on the other hand, cut the deposits completely free from the tubing and result in their complete removal from the well.

5 It is also an object of our invention to provide a scraper of the type indicated which has unusual structural strength. Another object of our invention is to provide a scraper having cutting elements which will not be interfered with by 10 the presence of obstructions in the tubing but which will pass by such obstructions and, after passing them, return to the normal cutting position.

A further object of our invention is to provide 15 a scraper which will give minimum interference with the flow of fluid.

Other and more detailed objects, advantages and uses of our invention will become apparent as the description thereof proceeds.

20 In general we accomplish these objectives by the use of wires as cutting elements and the wires are preferably constructed and arranged so that they will spring past obstructions and then return to their normal cutting positions. The use 25 of wires is highly advantageous as compared with the use of cutting knives or similar cutting elements which present large surfaces to the deposit, since the wires reduce the pull necessary to operate the scraper, thus eliminating the

30 breakage of scraping tools, and do not cause balling of the paraffin ahead of the cutting elements. Also the use of wire cutting elements makes it possible to do away with the necessity of using 35 separate spring members for the cutting elements, since the cutting element and spring can be made from a single piece of wire. Furthermore, the wire cutters can be so shaped and of such size and spacing as to give a scraping action over the complete surface of the tubing without 40 putting any undue strain on the scraper.

Our invention will now be further described in connection with the accompanying drawing which shows one preferred embodiment thereof and in which:

45 Figure 1a is an elevation partly in section of the upper portion of a scraper in accordance with our invention;

Figure 1b is an elevation partly in section of the lower end of this same scraper, the upper end of

50 Figure 1b corresponding to the lower end of Figure 1a;

Figures 2 and 3 are front and side elevations, respectively, of one of the cutting elements shown in the device of Figures 1a and 1b;

55 Figure 4 is a diagram illustrating one possible

arrangement of cutting elements in the device of Figures 1a and 1b;

Figure 5 is a detail in elevation showing one of the cutting elements in cutting position; and

Figure 6 is a detail in elevation showing one of the cutting elements in depressed position, as when passing an obstruction.

Our scraping tool as shown is made in three sections. The top section 21, in the form in which we have constructed it, is about 6 inches long. It is hollow and threaded at its lower end 22. This lower end terminates in a shoulder 23 cooperating with a similar shoulder on the central section 24 of our scraper. The hollow inside 25 of the top section has an upper shoulder 26 and communicates with an aperture 27. The purpose of this top section is to hold the end of the wire line on which the tool is operated. To fasten the scraper on the wire line the upper section 21 is unscrewed from the central section 24, the wire line 28 is slipped through aperture 27 and through the hollow interior 25 of the upper section and is knotted below it. This knot 29 is then drawn up into the upper section 21 where it comes to rest against shoulder 26. The central section 24 is then screwed onto the upper section 21 and the device is thus affixed to the wire line 28 and is ready to run in the conventional manner.

The middle section 24 is a steel shaft which, in the form used by us, is about 4 feet long. The principal purpose of this section is to give the tool weight which is of advantage in spudding it into the hole through the paraffined section of the tubing. Obviously if the tool is otherwise sufficiently heavy this section can be omitted and it is also possible, of course, to use a weighted section below rather than above the cutting section.

At the lower end of the central section 24 is a threaded joint 30, similar to that between sections 21 and 24, by which this central section is attached to the lower or cutting section 31.

Near its upper end section 31 carries a flat portion 32 which can be used in handling this section, for instance, by a wrench or the like.

The cutters 33 carried by this bottom section 31 are outline cutters and are made of tempered spring steel wire. These cutters are placed in keyways 34 and are keyed in place by pins 35 passing through holes in the walls of the keyways and also through holes 36 (Figure 3) in the cutting elements 33. It will be noted that the keyways do not pass completely through the body of the tool as in some prior art devices and we thus obtain improved structural strength.

As seen in Figures 2 and 3, each of the cutters 33 are preferably shaped from a single piece of wire which is bent to give a flat outline cutting head 37 and to form an opening or loop adjacent the cutting edge of the cutter, a spring section 38 (defining aperture 39) and a short projecting heel 39. The angle between the outline head portion 37 of cutter and the heel 39 is preferably about 90° or slightly more, depending in part on the shape of the back wall of keyways 34 against which heels 39 rest. In the form which we have used, the diameter of the tool shaft in all three sections is $\frac{3}{4}$ inch and the width of the outline head 37 of the cutters is $\frac{1}{2}$ inch, the cutters themselves being made of $\frac{3}{64}$ inch tempered spring steel wire.

These cutting elements are used in such numbers and at such spacings as to cut through the paraffin substantially completely around the in-

ternal circumference of the tubing 40 to be scraped. Thus in the form shown sixteen cutters are employed spaced $22\frac{1}{2}^\circ$ apart around the circumference of the tool. This specific device was designed for use in $2\frac{1}{2}$ inch tubing and it is thus apparent that the sixteen $\frac{1}{2}$ inch cutters will cover the complete internal circumference of the tubing. The length of the cutting elements is preferably such as to give about $\frac{1}{8}$ inch clearance with the internal walls of the tubing when the cutting element is standing straight outwardly.

As seen in Figure 1b the lower end 41 of our cutting tool is preferably tapered to assist in the insertion of the tool into the paraffined tubing.

It is preferable to arrange the cutting elements in opposed pairs so as to avoid any tendency for the cutting action to give unbalanced forces. Thus in the form shown in Figure 1b the two lowermost cutters are arranged 180° apart, making one of the opposed pairs.

Figure 4 illustrates diagrammatically one arrangement of these cutting elements. The lowermost cutting element is numbered 1 and the next higher one is numbered 2 and so on to the uppermost one which is numbered 16. The positions of the arrows in Figure 4 shows the circumferential spacing of these numbered cutters. Thus, the third cutting element from the bottom is spaced $22\frac{1}{2}^\circ$ from the first, the fifth is spaced $22\frac{1}{2}^\circ$ from the third, etc. Figure 1b shows only two of the eight opposed pairs of cutting elements, these pairs being made up of the first and second and ninth and tenth cutting elements denoted 33¹, 33², 33⁹ and 33¹⁰ respectively. Thus the cutting elements are spaced both longitudinally and circumferentially so as to give complete coverage, great structural strength, and balanced forces.

From the preceding description of our device its operation will largely be apparent. The device is dropped into a well on wire line 28 through the paraffined section of the tubing, the cutters 33 being forced into the position shown in Figure 1b by contact with the deposit. When the tool has passed below the paraffined section of the tubing, the cutting elements 33 will fall outwardly until heels 39 encounter the bases of keyways 34 at which point the cutter heads 37 will stand horizontally or preferably pointed upwardly at a slight angle as shown in Figure 5. If gravity should not cause the cutting elements to assume this position, they will assume it when their upper and outer edges encounter the surface of the paraffin as the tool is pulled upward since it will be noted that these upper and outer edges project beyond the keyways and are exposed to frictional contact with the paraffin. The result is that during the upward course of the tool the outline cutters stand out and each one cuts away its section of the paraffin 42 from the tubing 40 (Figure 5) thus making it possible for the up-flowing oil to disintegrate and remove the deposit.

When a cutting element encounters an obstruction 43 on tubing 40 (Figure 6) it springs downwardly (for instance to the position shown in Figure 6) until the obstruction is passed after which the spring action of the wire forces the cutter back to its cutting position (Figure 5).

Actual experience has shown that even in extremely badly paraffined wells the cutting tool of our invention permits the removal of the paraffin far more completely and expeditiously than do the scrapers heretofore used. The wire cutting elements not only give complete cutting but

prevent balling and undue frictional resistance because the paraffin, after having been cut away from the tubing, can pass through the loop or opening in the cutter, as shown in Figures 5 and 6, and consequently give minimum interference with the oil passing upwardly through the well, which, in turn, assists in the removal of the paraffin deposit.

Our scraper and modifications of it which will occur to those skilled in the art can likewise be used in scraping oil pipe lines which frequently contain paraffinic or other deposits.

While we have described our invention in connection with a specific embodiment thereof, it is to be understood that this is by way of illustration and not by way of limitation and that we do not mean to be restricted thereto except as indicated in the appended claims.

We claim:

1. A scraper for removing paraffin deposits and the like from the interior of a conduit, comprising a body portion having a plurality of keyways, an outline cutter mounted in each of said keyways, each of said outline cutters comprising a wire outline cutting head having a cutting edge

formed as a loop and a portion adapted to hold said head yieldingly in cutting position.

2. A scraper according to claim 1 in which said outline cutters are separated longitudinally from each other on said body portion and also placed circumferentially on said body portion to cover substantially the whole surface of the conduit to be scraped.

3. A scraper for removing paraffin deposits and the like from the interior of a conduit, comprising a body portion having a plurality of keyways, an outline cutter mounted in each of said keyways, each of said outline cutters comprising a wire outline cutting head having a cutting edge formed as a loop, a spring portion integral therewith and a heel portion integral with said spring portion adapted to cooperate with one of said keyways to hold said head yieldingly in cutting position.

4. A scraper according to claim 1 in which said outline cutters are mounted in said keyways by means of pins passing through said spring portion.
